UNITED STATES PATENT OFFICE.

OSCAR VEZIN, OF NEW YORK, N. Y.

MULTIPLE-CYLINDER STEAM-ENGINE.

SPECIFICATION forming part of Letters Patent No. 600,958, dated March 22, 1898.

Application filed May 27, 1897. Renewed January 25, 1898. Serial No. 667,841. (No model.)

To all whom it may concern:

Be it known that I, OSCAR VEZIN, a citizen of the United States, residing in the city of New York, county and State of New York, have invented certain new and useful Improvements in Multiple-Cylinder Steam-Engines, of which the following is a full, clear, and exact description, reference being had to the accompanying drawings, forming part of this specification.

In multiple-cylinder steam-engines it is essential to the effective service and durability of the engine that there be ample and uninterrupted lubrication of the crank-bearing, especially when the engine is run at high speed; and it is the object of this invention to provide means for the automatic, continuous, and abundant, and also economical, lubrication of such crank-bearing.

My invention is applicable to a multiple-cylinder steam-engine in which the cylinders are radially arranged on the engine-body about a common crank-shaft, with the arms of the several pistons of said cylinders engaging the crank within a chamber in said engine-body through which the exhaust-steam from said several cylinders passes in its escape; and my invention consists in the combination, with the engine-body bearing the several cylinders and having the aforesaid crank-chamber, together with a crank-shaft provided interiorly with a duct leading into a duct in the crank, with radial passages communicating with its circumference, of an auxiliary chamber communicating with the steam-exhaust aperture from the crank-chamber, having an outlet to the air and interiorly adapted to effect the separation from the water-vapor and the collection of the oil carried into said auxiliary chamber from the chambered engine-body, together with a tube leading from the lower end of said auxiliary chamber to and communicating with the duct in said crank-shaft.

In the drawings, Figure 1 is a rearward side elevation of a multiple-cylinder steam-engine containing my invention; and Fig. 2 is a vertical section of the same on the line xx , Fig. 1.

The engine shown in the drawings is one in which the several cylinders are single-acting on their inward stroke and in which the cylinder-ports are governed by slide-valves

driven by eccentrics on the common crank-shaft; but my invention is applicable to multiple-cylinder steam-engines in which there are variations from such stated structural features.

A is the engine-body, bearing the several cylinders a a' a^2 a^3 , which in the engine illustrated are radially arranged in pairs, with those of each pair on diametrically opposite sides of the common crank-shaft. The engine-body contains the chamber a^4 , which is closed in front by the head b and at the rear by the head b' , while a partition b^2 divides the chamber into two compartments, the rearward one of which constitutes the valve-chamber, apertures a^5 in the partition b^2 giving communication between the two compartments. The steam-chest a^6 is formed in said partition. The single common crank-shaft C has bearings in the head b and partition b^2 , and its crank is located in the forward compartment of the aforesaid engine-body chamber. The several cylinders on the engine-body open inwardly into said forward compartment of said chamber, similarly to the cylinder illustrated in Fig. 2, and the respective arms of the several cylinder-pistons engage the crank c in the aforesaid forward compartment of chamber a^4 , similarly to the arm a^7 of piston a^8 . (Shown in Fig. 2.) Each cylinder has an inlet and exhaust port, such as shown at a^9 , Fig. 2. The cylinder and steam-chest ports, one of the latter being seen at a^{10} , Fig. 2, are governed by an ordinary form of slide-valve D , operated through a rod d , worked by an eccentric D' on the crank-shaft, as illustrated in Fig. 2, and said valves may be furnished with adjustable balance-plates. (Shown at d' .)

A further description of the structure or operation of the engine illustrated in the drawings is unnecessary, as the same are well known and will be readily understood from that above given.

The shaft C and its crank c are adapted for the uses and purposes of my invention by means of a duct c' , extending longitudinally through the shaft, preferably from its rearward end, to and into the body of the crank, with passages c^2 extending radially in the crank to its circumference.

In carrying out my invention I combine with the described engine-body bearing the

said several cylinders and containing the chamber within which the said crank provided with the said duct plays, and through which the exhaust-steam from said several 5 cylinders circulates, an auxiliary chamber E, the inlet e of which, preferably at its bottom, communicates with the exhaust-aperture a¹¹ of the chamber a⁴ and the outlet of which, as at e', preferably at its top, opens into the air, 10 and this chamber is interiorly adapted in any well-known manner to separate from the water-vapor and to collect any oil which may be carried by the exhaust-steam from the chamber a⁴ into said chamber E. The chamber E 15 may be, for the purposes stated, provided with the tube e², extending from the inlet part way of the interior height of the chamber, a hood e³, placed above the upward end of said tube and extending downwardly around the same 20 toward the chamber-bottom and between the tube and the surrounding chamber-wall, and inclined annular flanges e⁴, respectively arranged in series upon adjacent surfaces of the tube and hood and the hood and chamber- 25 wall, as shown.

Exhaust-steam from chamber a⁴, entering through tube e², will impinge upon the inner face of the top of the hood e³, and hence be deflected against the inner face and diffused 30 within the depending rim of said hood, passing thence into the space between the outer face of the hood and the inner face of the chamber-wall, and the oil carried by said exhaust-steam will be deposited upon the 35 surfaces of the hood and chamber-wall and the described inclined flanges and will flow thence to and collect in the lower part of said chamber, while the water-vapor, freed from the oil, will escape at the chamber-outlet e'.

Any other known means for interiorly adapting the chamber E to effect the separation of the oil from the vapor of the exhaust-steam and its collection therein may be employed in place of the particular devices herein shown and described in carrying out my present invention without material variation from the essential feature thereof. In further carrying out my invention I combine with the said chamber E, the chambered engine-body, 45 and the shaft and crank provided with the described duct and passages a tube E', leading from the lower part, preferably at or near the bottom of said chamber E, to and communicating with the duct c' in said crank-shaft, 50 and in the engine shown the tube E' may be extended through a suitable stuffing-box a¹², in the rearward head b' of the engine-body, 55 into the aforesaid duct, its end resting loosely therein. An oil-cup E² may be advantageously 60 arranged to feed, if required, into the tube E'.

The operation of the devices constituting the invention is as follows: When the engine is initially started in motion, oil in adequate quantity is fed into the tube E', as from the 65 cup E², and passes thence into the duct c' in shaft C and to crank c, where it is thrown out through the passages c² to and lubricates the

crank-bearings. As the oil escapes from the bearings into the chamber a⁴ it therein mingles with and is more or less taken up by the exhaust-steam circulating through said chamber and is thereby carried into the auxiliary chamber E. In said chamber E the oil is, as before set forth, separated from the vapor and collected in the bottom of said chamber, 70 whence it flows through tube E' into the crank-shaft duct c' and again passes to and lubricates the crank-bearing. When an adequate supply of oil has been fed into the tube E', as from the cup E², as described, the supply may be cut off or reduced to an exceedingly small quantity, and the oil within the engine will pass successively from the chamber E to the crank-bearings and thence to chamber a⁴ and be therein taken up and carried more or less by the exhaust-steam into chamber E, so that the circulation of the oil within the engine will be automatic and continuous and will with economy effect the ample and uninterrupted lubrication of the 80 crank-bearings.

I make no claim to novelty in a crank-shaft provided with a lubricator-duct; nor do I make claim to novelty in the herein-described devices for separating oil from the water-vapors of exhaust-steam; but I intend it to be understood that my invention specifically relates to a multiple-cylinder steam-engine in which the several cylinders are carried by an engine-body containing a chamber in which the crank common to the piston-arms of the several cylinder-pistons plays and into which the exhaust from said cylinders passes, and that my invention specifically consists in the combination, with such a chambered engine-body and the said shaft and crank provided with the described lubrication duct and passages, of an auxiliary chamber having an inlet communicating with the exhaust-aperture from said crank-chamber and an outlet to the air and interiorly adapted to separate from the water-vapors and to therein collect oil which may be carried thereto by the exhaust-steam from said crank-chamber, together with a tube establishing communication between the lower part of said auxiliary chamber and said crank-shaft duct, whereby the oil for lubricating the crank-bearings will, as it escapes therefrom into the crank-chamber and is therein taken up by the exhaust-steam and carried (more or less) thereby into said auxiliary chamber, wherein it is separated from the water-vapors and collected, be returned to the crank-bearings, and whereby this circulation of the oil within the engine-body will be automatically continuous and will with economy effect the uninterrupted and ample lubrication of the crank-bearings; and it is to the invention comprising these features in combination that I herein make 115 claim.

What I claim as my invention, and desire to secure by Letters Patent, is—

In a multiple-cylinder steam-engine com-

prising an engine-body bearing the several cylinders and containing a chamber in which the crank of the shaft common to all the cylinder-pistons has play, and through which the exhaust-steam from the several cylinders passes, together with the crank and its shaft provided with a lubrication duct and passages leading to the circumference of the crank, the combination therewith of an auxiliary chamber having an inlet communicating with the exhaust-aperture of the crank-chamber and an outlet communicating with the air, and interiorly adapted to separate from the water-vapors and therein collect oil carried thereinto from said crank-chamber

by the exhaust-steam, together with a tube establishing communication between the lower part of said auxiliary chamber and said shaft-duct; whereby oil carried by the exhaust-steam from the crank-chamber will be returned to the crank-bearings and such circulation of the oil within the engine will be automatically continuous and will effect the uninterrupted lubrication of the crank-bearings; substantially as and for the purpose specified. 25

OSCAR VEZIN.
